SELF-LOCKING SHELF AND PRICE TAG MOLDING ASSEMBLY

Edward C. Streater, Mound, Minn.

Application July 22, 1957, Serial No. 673,377

5 Claims. (Cl. 211—147)

This invention relates to shelf assemblies, and more particularly to a self-locking shelf and price tag molding assembly.

The special molding of the instant invention is intended to be utilized with simple shelving and bracket means having rearwardly biased clamping abutments such as disclosed in my co-pending application, Serial No. 449,065, filed August 11, 1954, now U.S. Patent No. 2,833,420.

It is a general object of the invention to provide a shelf assembly which is simple to construct and erect and which will provide means for exhibiting prominently at the forward edge of a shelf the price of articles and other information relating thereto and in association with the articles in their supported position.

More specifically, it is an object of the invention to provide a price tag molding strip which will cooperate in the reinforcing and supporting of the shelf member, particularly thin shelving members such as may be constructed from glass.

A still further object of the invention is to provide a shelf assemblage wherein the shelf is supported from underneath the brackets and is supported at its forward edge by a price tag molding strip, the entire assemblage being firmly retained and interlocked together with relation to a vertical supporting surface by simple biased abutment means.

These and other objects and advantages of the invention will more fully appear from the following description, made in connection with the accompanying drawings, wherein like reference characters refer to the same parts throughout the several views and in which:

Figure 1 is a perspective view taken from below of a section of my assembly, the shelf and price tag molding being held in interlocked engagement with the vertical supporting surface;

Figure 2 is a bottom view of my shelving assembly shown segmentally, the dotted lines indicating the positions of the bracket members in relaxed condition where-in the shelf and molding are not locked in place; and

Figure 3 is an enlarged vertical section of a segment of my shelving assembly taken on the line 3—3 of Figure 1.

With continued reference to the drawing, my shelving assembly is intended to be mounted on a vertical supporting surface indicated generally at 10. Where the assemblage is vertically adjustable, I may employ bracket support members 11 as a part of the vertical surface, the bracket support members being provided with vertically spaced slots 12 capable of receiving bracket members which may be cooperatively secured therewith in the manner set forth in my above mentioned U.S. Patent No. 2,833,420.

Referring to Figure 2, the bracket supports 11 may be fastened as by screws 13 to a back panel 14, a portion of which has been grooved or offset at 15 to receive the bracket supports. The bracket supports 11 are vertically

positioned and horizontally spaced at convenient intervals which may be associated with the edges of the back panel 14 or may be recessed at intermediate positions with the forwardly facing portion thereof substantially in alignment with the forward surface of the back panel 14 and cooperatively forming the aforementioned vertical supporting surface 10.

The shelf proper may constitute a board or panel 16, and it is within the contemplation of this invention that 10 the shelf 16 range in thicknesses down to that of ordinary glass paneling. The shelf 16 has an upper supporting surface 17, as shown in Figure 3, and further has a rear edge 18 adapted to abut against the vertical supporting surface 10 and a forward edge 19 as shown in Figure 15. The shelf 16 is intended to support articles (not shown) and may be horizontally disposed or angulated for the intended purpose.

Secured to the vertical supporting surface 10 are bracket members 20 which are shown in Fig. 2 in operative 20 positions in full lines and which may comprise the same type of sprung members disclosed in my U.S. Patent No. 2,833,420, or any other type of bracket means securable to a vertical supporting surface and capable of supporting a shelf member 16.

Each bracket member 20 has an abutment 21 which is upstanding with relation to the shelf supporting edge 22. The front portions of bracket members 20 extend, in relaxed condition, obliquely in relation with the rear portions which are normally oriented substantially normal 30 to the vertical support and which are secured as by ears or hooks 23 inserted into the slots 12 of the bracket supports 11. The rear portions of members 20 have laterally extending abutment or ear means 24 adapted to brace the bracket members 20 against horizontal swinging so as 35 to permit the front portions of the bracket members to be resiliently flexed from the dotted (relaxed) position of Fig. 2 to the full line position wherein the tendency to return to the dotted line position provides rearward biasing of the upstanding abutments 21. It is understood, 40 of course, that any other type of bracket means having a forward abutment 21 which is rearwardly biased may also be employed for purposes of the present invention.

An important part of the invention lies in the price tag molding strip 25 which performs the cooperative functions set forth below in connection with the shelf 16 and the bracket means 20. The price tag molding 25 is generally elongated and provided with a rearwardly extending channel 26 adapted to receive the forward edge 19 of shelf 16 and thereby lend support to the shelf, particularly where the shelf is thin and has a tendency to bend when supporting articles are disposed thereover. The rearwardly extending channel has an upper flange 27 and a lower flange 28 adapted to bear against the upper and lower marginal areas of edge 19 and are preferably tightly wedged thereagainst.

The price tag molding strip also is provided with a frontal tag holding means 29 which may be in the form of a concave elongated groove or track, the upper and lower edges 30 and 31 respectively of which provide edge-gripping members for price tags and the like to be inserted therin.

The price tag molding strip 25 is also provided with means for cooperating with the rearwardly biased abutment 21 and such may conveniently take the form of an upwardly formed groove 32 formed intermediate the channel 19 and the frontal tag holding portion 29, as shown in Figure 3. The groove 32 has an area 33, at least a portion of which extends forwardly and is adapted to be engaged by the rearwardly biased abutment 21 when the bracket members 20 are sprung to the full line positions shown in Figure 2. A notched outer area 34 may

be formed in the upper edge 22 of bracket member 20 to receive the lower flange 28 of the rearwardly extending channel portion 19.

In the mounted condition of the price tag molding strip, as shown in Figure 3, it will be observed that the bracket member 20 retains the molding strip firmly interlocked against the edge 19 of the shelf 16 and that the entire shelf assembly is thus held rigidly with respect to the supporting surface 10 without the aid of any additional fastening members. The price tag molding strip 25 not only serves to retain identifying tags in association with particular shelf locations, but also supports the front edge 19 of shelf 16 and has abutment means adapted to cooperate with a rearwardly biased abutment associated with the shelf brackets 20. In the instant case, the brackets 20 simply provide their own biasing means through the laterally bent configuration, utilizing the upstanding abutment 21 and the sprung positioning of the bracket to place the entire assemblage under stress.

It will, of course, be understood that various changes may be made in the form, details, arrangements and proportions of the parts without departing from the scope of my invention.

What I claim is:

1. A self-locking shelf assembly for mounting forwardly on a vertical support comprising, a shelf having an upwardly facing supporting surface and a rear edge for abutting a vertical support and a forward edge, bracket means, means for rigidly securing said bracket means to a vertical support to extend forwardly thereof in supporting relation with said shelf, said bracket means supporting said shelf and having a forward abutment means on the bracket normally biasing the abutment rearwardly, an elongated molding strip having a shelf edge engaging portion interfitting with the forward edge of said shelf and forwardly facing tag holding means, said molding strip further being provided with abutment means providing a forwardly facing surface cooperatively engaged by the rearwardly biased bracket abutment whereby the shelf, bracket means, and molding strip are firmly interlocked and connected to said bracket securing means.

2. A self-locking shelving assembly for mounting forwardly on a vertical support comprising, a shelf having an upwardly facing supporting surface and a rear edge for abutting a vertical support and a forward edge, bracket means, support means for rigidly securing said bracket means to such a vertical support to extend forwardly thereof in supporting relation with said shelf, said bracket means supporting said shelf and having an upstanding abutment positioned forwardly thereon, said bracket means having means normally biasing the abutment rearwardly, an elongated molding strip having a shelf-engaging portion interfitting with the forward edge of said shelf and a forwardly facing tag holding means, said molding strip further being provided with an upwardly formed groove extending longitudinally in the underside thereof, said groove having a forwardly facing surface arranged in cooperative clamping engagement with the rearwardly biased upstanding abutment of said bracket means whereby the shelf, bracket means and molding strip are firmly interlocked and connected to said support means.

3. A self-locking shelving assembly for mounting forwardly on a vertical support comprising, a shelf having an upwardly facing supporting surface and a rear edge

for abutting a vertical support and a forward edge, bracket means, support means for rigidly securing said bracket means to such a vertical support to extend forwardly thereof in supporting relation with said shelf, said bracket means supporting said shelf and having a forward abutment said bracket means having means normally biasing the abutment rearwardly, an elongated molding strip having a rearwardly formed channel interfitting with the forward edge of said shelf and forwardly facing tag holding means, said molding strip further being provided with an upwardly formed groove extending longitudinally at the underside thereof, said upwardly formed groove lying between the rearwardly formed channel and the forwardly facing tag holding means and including a clamping surface cooperatively engaged by the rearwardly biased bracket abutment whereby the shelf, bracket means and molding strip are firmly interlocked and connected to said support means.

4. A self-locking shelf assembly comprising a vertical support, a shelf having an upwardly facing supporting surface and having a rear edge and a forward edge, bracket means mounted on said vertical support and extending forwardly thereof in supporting relation with said shelf, said bracket means having a molding strip engaging element formed on its forward end and the bracket means also having means normally biasing said element rearwardly, and an elongated molding strip having a shelf edge engaging portion engaging the forward edge of said shelf and having forwardly facing tag holding means, said molding strip further being provided with abutment means including a forwardly facing surface cooperatively engaged by said rearwardly biased molding strip engaging element of said bracket whereby said shelf, bracket means, and molding strip are firmly interlocked and supported in forwardly extending relation to said vertical support.

5. A self-locking shelf assembly for mounting forwardly on an upright support, comprising a shelf having an upwardly facing supporting surface and a rear edge portion for abutting an upright support and a forward edge, bracket means, means for rigidly securing said bracket means to an upright support to extend forwardly thereof in supporting relation with said shelf, said bracket means supporting said shelf and having a forward abutment, said bracket means having means normally biasing the abutment rearwardly, an elongated molding strip having a shelf edge engaging portion interfitting with the forward edge of said shelf, said molding strip further being provided with abutment means providing a forwardly facing surface cooperatively engaged by the rearwardly biased bracket abutment whereby the shelf, bracket means, and molding strip are firmly interlocked and connected to said bracket-securing means.
